WIRE KNOTTING MACHINE

Application filed January 12, 1931. Serial No. 508,077.

The present invention relates to a machine for knotting or tying the free end of a wire article, such as a coiled spring, and has for its object to provide a machine of the above indicated character that is simple and effective in its operation. The machine is particularly characterized by the fact that it is adapted to present a wire article, such as a spring, to the knot tying, or twisting, tool in such a manner that it is properly positioned and firmly held in advance of the knotting operation, thereby entirely eliminating any possibility of the operator's hand being drawn into the moving parts of the machine. Furthermore, the machine is capable of ready adjustment for operating on different sizes of wire and other advantageous features of the machine will hereinafter more fully appear from the following description with reference to the accompanying drawings, in which:—

Fig. 1 is a plan view of a machine embodying the invention.

Fig. 2 is a view in front elevation of the machine shown in Fig. 1.

Fig. 3 is a view in end elevation of the machine shown in Fig. 2, as viewed from the left.

Fig. 4 is a horizontal sectional view along the line 4—4 of Fig. 3, looking in the direction of the arrows.

Fig. 5 is a fragmentary view illustrating the mounting of the work table, certain parts being removed.

Fig. 6 is a fragmentary sectional view along the line 6—6 of Fig. 1, looking in the direction of the arrows.

Fig. 7 is a fragmentary sectional view, illustrating the formation of a knot on a spring.

Fig. 8 is a view similar to Fig. 7, showing the formation of a different type of knot by adjustment of the machine.

Figs. 7a and 8a illustrate the completely formed knots resulting from the different operations of Figs. 7 and 8.

Like reference characters refer to like parts throughout the drawings.

Referring to the drawings, the machine generally comprises a frame 1 providing up-

wardly extending bearing brackets 2, 2 for rotatably supporting a driving shaft 3 and a cam shaft 4. Power is adapted to be applied to the machine from any suitable source by means of a pulley 5 which, as best shown in Fig. 4, is loosely mounted on the shaft 3 and is adapted to be operatively connected to the shaft 3 by means of a suitable clutch device 6, the details of which will be herein-after more fully described. The shaft 3 has keyed thereto a pinion 7 in mesh with a gear 8 mounted on the cam shaft 4, the ratio between the pinion 7 and gear 8 being such that cam shaft 4 is adapted to make one-half of a revolution for each complete revolution of the drive shaft 3.

As best shown in Figs. 1, 3 and 5, the machine provides a flat work supporting table 9 providing a downwardly extending portion 10 carrying a dovetail gib 11 slidably received in a correspondingly shaped slot 12a formed in an arm 12 secured to the frame bracket 2 by bolts 13 received in elongated slots 13a, so that the arm 12 and table 9 are capable of vertical adjustment, as a unit. The table 9 is adapted to be given a reciprocatory movement in a horizontal plane by means of a two-armed lever 14 pivotally mounted on a rockshaft 15 with one arm 14a of the lever extending upwardly beneath the outer end of the table 9. As best shown in Fig. 4, the

upper end of the lever arm 14a carries a pivoted block 16 through which passes a rod 17 longitudinally adjustable in the block 16 by means of nuts 18 in threaded engagement with the rod 17 on opposite sides of the block 16. The other end of the rod 17 is rigidly received in a wrist pin 19, the ends of which are rotatably supported in lugs 20 provided by the under side of the work table 9. With the above described connection between the table 9 and the lever 14, turning of the lever about its rock shaft 15 imparts a horizontal movement to the table, the limits of this movement being capable of adjustment by reason of the longitudinal adjustability of the rod 17 within the block 16.

The other arm 14b of the lever 14 carries at its end a roll 21 which is received in a track 22 provided on a cam 23 mounted on the

- shaft 4. The track 22 of the cam 23 is so formed that when the shaft 4 is turned through one complete revolution in the direction of the arrow, starting with the parts in the position shown in Fig. 3, the table 9 will be moved toward the drive shaft 3 during the first quarter of the revolution of the shaft 4. Then during the next one-half of a revolution of the shaft 4, the table will remain stationary, after which the next one-quarter revolution of the shaft 4 will return the table 9 to the position shown in Fig. 3. In other words, each complete revolution of the cam shaft 4 will impart a complete reciprocatory movement to the table 9, with a dwell between the inward and outward movements of the table 9 with respect to the shaft 3. And since the shaft 4 is adapted to make only one-half of a revolution for each complete revolution of the drive shaft 3, the table 9 will remain in its inward position for a period corresponding to the period for one revolution of the drive shaft 3.
- As best shown in Fig. 1, the table 9 carries on its surface one or more adjustable work positioning blocks 24, 24 arranged to substantially fit the curvature of the end convolutions of a coiled spring, indicated in dotted lines at 25, when the base of the spring is placed on the table 9. The table 9 also provides a slide 26 carrying a stop 27 for the free end of the last convolution of the spring 25, the slide 26 being longitudinally movable in a slot 9a provided in the face of the table 9. As best shown in Fig. 6, the end of the slide 26 provides a lug 28 which is connected to a fixture 29 mounted on the frame by a pin 30a passing through ears 30 of the fixture 29, so that the slide 26 does not move with the table 9. The fixture 29 is adjustably mounted on the frame by a bolt 29a passing through a slot. The table 9 also carries a clamping block 31 having a groove 31a therein for receiving a portion of the next to the last convolution of the spring 26 adjacent to its free end when the latter is in engagement with stop 27.
- As best shown in Fig. 3, a movable clamp 32 is adapted to cooperate with the clamping block 31 to grip the end convolutions of the spring during the knotting operation and this clamp 32 is freely supported at the end of an arm 33 mounted on a pin 34 carried by a bracket 35 extending upwardly from the side of the table portion 10. The bracket 35 is secured to the table portion 10 by bolts 36 received in elongated slots 36a, so that the bracket 35 is capable of vertical adjustment. A spring 37 connected to the arm 33 and anchored at its other end on the table portion 10 serves to bias the arm 33 in the position shown in Fig. 3, in which the clamp 32 is raised above the block 31. In this position, the upper surface of the arm 33 is yieldingly maintained in engagement with a roll 38 car-

ried at one end of a lever 39 pivotally supported on a stud 40 projecting laterally from a housing 41 inclosing the knotting tool, hereinafter described. The end of the lever 39 opposite to the roll 38 carries a bolt 42 for clamping to the lever 39 an arm 43 carrying at its end a roll 44 bearing on the outer surface of the cam 23.

In the position shown, the roll 44 is received in a depression 45 provided in the outer surface of the cam 23 so that the spring 37 maintains the clamp 32 in its raised position. However, when rotation of the shaft 4 from the position shown in Fig. 3 causes the table 9 to start its inward movement toward the shaft 3, the arm 43 is moved upwardly by the cam 23 and this movement of the arm is imparted to the lever 39. Therefore, as the table 9 starts to move inwardly carrying a spring toward the knotting tool housing 41, the roll 38 at the end of the lever 39 exerts a downward pressure on the arm 33, thereby causing the clamp 32 to firmly engage the end convolutions of the spring in cooperation with the clamping block 31. This clamping engagement is maintained the entire time that the table remains in the spring knotting position, the knotted spring not being released until the table 9 is again moved outwardly to the position shown in Fig. 3 wherein the roll 44 is again seated in the depression 45. The arm 43 is adjustable about the clamping bolt 42 and an overhanging lug 46 on the lever 39, see Fig. 1, carries a stud 47 for maintaining any adjustments which may be made for operating on different sizes of wire.

Referring now to Fig. 4, the housing 41 incloses a gear 48 mounted on a sleeve 49 loosely surrounding a reduced portion 3a of the shaft 3. The teeth of the gear 48 are in mesh with the teeth of a knotting pinion 50 also rotatably supported by the housing 41. The knotting pinion 50 is of a form usually employed in machines of this type and provides a conical recess 51 and a radial recess 52 at opposite ends connected by a radial slot 53, the slot 53 being alined with the surface of the clamping block 31 when the parts occupy the position shown in Fig. 3. Consequently, when the table 9 is moved inwardly, during the first quarter of a revolution of the shaft 4, the inner convolutions of the spring enter into the conical recess 51, as shown in Fig. 7, which movement causes the shoulder 54 between the recess 51 and recess 52 to bend the free end of the spring at right angles to the axis of the conical recess. This movement also shifts the end of the wire away from the stop 27, the fixed plate 26 sliding in the slot 29, as the table 9 moves to its extreme inner position. The ratio between the teeth on the gear 48 and the pinion 50 is such that each complete revolution of the gear 48 causes the knotting

pinion 50 to make two complete revolutions, and the manner in which the gear 48 is driven from the shaft 3 will now be described.

As best shown in Fig. 4, the sleeve 49 carrying the gear 48 is keyed to a collar 55 carrying a slideable dog 56 pressed by a spring 57 in the direction of the pinion 7 which drives the cam shaft 4. The face of the pinion 7 opposing the dog 56 provides a notch 58, so that movement of the dog 56 toward the pinion 7 by the spring 57 will cause the dog 56 to enter the notch 58 and establish a driving connection between the collar 55 and the pinion. As best shown in Fig. 2, the dog 56 is adapted to be maintained in a position in which it is withdrawn from the notch 58 by means of a bolt 59 receivable in a groove 60 provided in the collar 55, the bolt 59 providing a beveled end portion 59a adapted to hold the dog retracted in the position shown. The bolt 59 is carried at the end of one arm of a lever 61 having its middle portion mounted on a countershaft 62 extending below the drive shaft 3 in front of the cam shaft 4. The other arm of the lever 61 extends rearwardly in the direction of the cam shaft 4 and cooperates with a collar 63 carried by the shaft 4, the collar 63 providing a cam projection 64 which is adapted to turn the lever 61 and operate the bolt 59.

As previously pointed out, the shaft 3 carrying the pinion 7 is adapted to be connected to the pulley 5 by means of a clutch 6 which comprises a collar 65 keyed to the shaft 3. The collar 65 carries a slideable dog 66 which is pressed in the direction of a notch 67 on the hub of the pulley 5 by means of a spring 68. As best shown in Fig. 2, a bolt 69 movable in a groove 70 on the collar 65 serves to hold the dog 66 withdrawn from the notch 67. The bolt 69 is carried at the end of one arm of a lever 71 carried by the countershaft 62 on which the lever 61 is also mounted. The other arm of the lever 71 extends rearwardly toward the shaft 4 with its free end cooperating with a collar 72 mounted on the shaft 4, a cam projection 73 on the collar 72 serving to turn the lever 71, see Fig. 1.

The countershaft 62 carrying the clutch operating levers 61 and 71 also carries a forwardly extending arm 74 that is connected by a link 75 to a foot treadle 76 pivotally supported at the bottom of the frame 1. By depressing the treadle 76 the arm 74 is turned downwardly, thereby turning the shaft 62 and causing the lever 71 to draw the bolt 69 downwardly in the groove 70. When this occurs, the dog 66 is projected in the notch 67 as soon as the turning of the pulley 5 brings the notch 67 in alignment with the dog 66. The shaft 3 is then driven by the pulley 5 which in turn drives the cam shaft 4 at one-half the speed of rotation. Assuming that the parts occupy the posi-

tion of Fig. 3 when the treadle 76 is depressed, following the positioning of a spring on the table 9, the first one-half revolution of the shaft 3 causes the lever 14 to move the table 9 and carry the spring into the slot 53 of the knotting pinion 50. The pinion 50 at this time is held stationary by the cooperation of a locking plunger 77 with the collar 55, see Fig. 1, which insures that the pinion slot 53 will properly receive the spring. After the table 9 has positioned the spring within the pinion 50 it comes to rest due to the fact that the portion of the cam track 22 with which the roll 21 is then in engagement is concentric about the axis of the shaft 4 and the table 9 remains stationary throughout one complete revolution of the drive shaft 3.

By the time that the spring 25 has been positioned in the stationary pinion 50, the notch 58 in the pinion 7 has been engaged by the dog 56, so that the collar 55 is clutched to the pinion 7. Just prior to this, the plunger 77 is raised by a lever 78 operated by a cam 79 on the shaft 4, so that the collar 55 is free to turn with pinion 7 and the sleeve 49 imparts rotative movement to the knotting pinion 50 thereby wrapping the free end of the wire coil around the first convolution, as indicated diagrammatically in Fig. 7. After the pinion 7 has completed substantially one revolution with the collar 55 clutched thereto, the cam projection 64 on the collar 63 engages the lever 61 and causes the bolt 59 to withdraw the dog 56, thereby arresting rotation of the knotting pinion 50. By this time, however, the pinion 50 has completed two revolutions, so that as it comes to rest with the slot 53 in the position shown in Fig. 4, the knotted spring can be withdrawn. The spring withdrawal movement of the table 9 is brought about by the engagement of the roll 21 with the remaining portion of the cam track 22 which is effective during the last one-half of the revolution of the drive shaft 3. As the drive shaft 3 completes its second revolution, the projection 73 on the collar 72 operates the lever 71, thereby causing the bolt 69 to withdraw the dog 66 from the notch 67 in the pulley 5. The machine, therefore, comes to rest with all of its parts occupying the position of Fig. 3 for the beginning of a new cycle of operation which is repeated each time a spring is positioned on the table 9 and the foot treadle 76 depressed.

As previously pointed out, the operation of the machine is such that the wire springs are operated upon without any possibility of the operator's hand being drawn into the moving parts of the machine. This particular feature is clearly evident from a consideration of Fig. 1, in which a wire spring, indicated in dotted lines at 25, is shown as having been positioned on the table 9, when the table is at rest in its outer position. In positioning a spring on the table 9, in the manner shown,

- the operator has only to position the free end of the spring in engagement with the stop 27, with its inner convolutions engaging the block 31. Then as soon as the foot treadle 76, is depressed, cam 23, acting through the lever 39, immediately causes the clamp 32 to firmly hold the spring in cooperation with the block 31. The spring being thus firmly held as the table 9 starts to carry the spring inwardly, the operator is immediately relieved of any necessity of having the hands follow the table. Furthermore, the slide 26, carrying the stop 27, remains stationary as the table 9 moves inwardly, so that the operator's hands naturally come to rest on stationary slide 26, after positioning a spring. As a result, any possibility of the operator's hands being drawn into the moving parts of the machine is eliminated.
- 20 In operating on springs wound from wire of different diameters, the adjustment of the arm 43 of the operating lever 39 permits the movement of the clamp 32 to be so controlled as to insure the proper holding pressure on the wire between the block 31, and the clamp 32. Furthermore, the vertical adjustment of the bracket 35, carrying the pivot 34, makes it possible to insure that the arm 33, carrying the clamp 32, will assume a horizontal position parallel to the table 9, when the roll 44, of the arm 43, is riding on the surface of the cam 23. Otherwise, the clamp 32, would tend to release its grip on the wire.
- 21 In addition to the above described adjustments, it is also possible to obtain close adjustment of the travel of the table 9, without changing the cam track, 22. By varying the length of the rod 17, by means of the nuts 18 on opposite sides of the block 16, the travel of the table 9 can be readily changed for the purpose of causing the free end of the spring to be wound around the next adjacent convolution with the desired amount of gripping effect. For example, as shown diagrammatically in Fig. 7, the inward travel of the table 9, is such that in its extreme position, the innermost coil of the wire is positioned coaxially with the knotting pinion, 50. Therefore, when the pinion 50 is rotated, the deflected end of the wire will be wound evenly around the adjacent convolution, see Fig. 7a. In some cases, however, it is desirable to obtain a locking effect between the end convolution and the turns of wire which are wrapped about it, as illustrated in Fig. 8. In order to obtain this locking, the connecting rod 17, is shortened by means of the nuts 18, so that the table 9, does not move in as far as it does in Fig. 7. Therefore, the end convolution of the spring comes to rest somewhat off center within the pinion 50, so that when the free end of the wire is wrapped around the same, the wire of the end convolution will be offset where the wrapping occurs, see Fig. 8a. As a result, the turns

of wire will be firmly locked on the end convolution so that the knot on the spring cannot be displaced.

We claim,

1. In a machine of the class described, the combination with a frame, a rotatably mounted shaft and a knotting pinion adapted to be driven from said shaft, of a spring supporting table adapted for reciprocatory movement in a horizontal plane at right angles to the axis of rotation of said knotting pinion. 70
2. In a machine of the class described, the combination with a frame, a rotatably mounted shaft and a knotting pinion adapted to be driven from said shaft, of a spring supporting table slidably mounted on said frame for movement in a horizontal plane at right angles to the axis of said pinion, and means for adjustably controlling movement of said table. 80
3. In a machine of the class described, the combination with a frame, a rotatably mounted shaft and a knotting pinion adapted to be driven from said shaft, of a spring supporting table slidably mounted on said frame and means for imparting a reciprocatory movement to said plate in a horizontal plane at right angles to the axis of said knotting pinion. 90
4. In a machine of the class described, the combination with a frame, a rotatably mounted shaft and a knotting pinion adapted to be driven from said shaft, of a spring supporting table slidably mounted on said frame, a rocking lever pivotally mounted on said frame, means for imparting an oscillatory movement to said lever and a connection between said lever and said table for translating the oscillatory movement of said lever into reciprocatory movement of said table in a horizontal plane at right angles to the axis of said knotting pinion. 93
5. In a machine of the class described, the combination with a frame, a rotatably mounted shaft and a knotting pinion adapted to be driven from said shaft, of a spring supporting table slidably mounted on said frame, a rocking lever pivotally mounted on said frame, a cam driven from said shaft for imparting an oscillatory movement to said lever and a connection between said lever and said table for translating the oscillatory movement of said lever into reciprocatory movement of said table in a horizontal plane at right angles to the axis of said knotting pinion. 100
6. In a wire knotting machine, the combination with a spring supporting table movable in a horizontal plane and carrying a wire clamping block, of a clamping member pivotally mounted on said table, and means for turning said clamping member into engagement with said block in advance of movement 110
7. In a wire knotting machine, the combination with a spring supporting table movable in a horizontal plane and carrying a wire clamping block, of a clamping member pivotally mounted on said table, and means for turning said clamping member into engagement with said block in advance of movement 120
8. In a wire knotting machine, the combination with a spring supporting table movable in a horizontal plane and carrying a wire clamping block, of a clamping member pivotally mounted on said table, and means for turning said clamping member into engagement with said block in advance of movement 125
9. In a wire knotting machine, the combination with a spring supporting table movable in a horizontal plane and carrying a wire clamping block, of a clamping member pivotally mounted on said table, and means for turning said clamping member into engagement with said block in advance of movement 130

of said table into the wire knotting position.

7. In a wire knotting machine, the combination with a spring supporting table movable in a horizontal plane and carrying a wire clamping block, of a clamping member pivotally mounted on said table, means for maintaining said clamping member out of engagement with said block when the table is in the spring receiving position, and means for moving said clamping member into engagement with said block before said table is moved to the wire knotting position.

8. In a wire knotting machine, the combination with a spring supporting table movable in a horizontal plane and carrying a wire clamping block, of a clamping member pivotally mounted on said table, and a pivotally mounted lever yieldably maintained in contact with said clamping member for moving said clamping member into engagement with said block before said table is moved to the wire knotting position.

9. In a wire knotting machine, the combination with a rotatably driven shaft, a knotting pinion adapted to be driven from said shaft and a work supporting table adapted to have a horizontal reciprocatory movement imparted thereto from said shaft, of a clamping member pivotally mounted on said table and means operated from said shaft, in timed relation with the table moving means, for moving said clamping member into engagement with a wire article on said table in advance of the movement of said table into the wire knotting position.

10. In a wire knotting machine, the combination with a rotatably driven shaft, a knotting pinion adapted to be driven from said shaft and a work supporting table adapted to have a horizontal reciprocatory movement imparted thereto from said shaft, of a clamping member pivotally mounted on said table, a cam driven from said shaft and a lever operated by said cam for turning said clamping member into engagement with a wire article on said table in advance of movement of said table into the wire knotting position.

11. In a wire knotting machine, the combination with a rotatably driven shaft, a knotting pinion adapted to be driven from said shaft and a work supporting table adapted to have a horizontal reciprocatory movement imparted thereto from said shaft, of a clamping member pivotally mounted on said table, a cam driven from said shaft, a lever operated by said cam for turning said clamping member into engagement with a wire article on said table and means for adjusting said clamp operating lever independently of said cam to variably control the clamping pressure.

12. In a wire knotting machine, the combination with a rotatably driven shaft, a knotting pinion adapted to be driven from said shaft and a work supporting table adapt-

ed to have a horizontal reciprocatory movement imparted thereto from said shaft, of a bracket vertically adjustable on said table, a clamping member pivotally mounted on said bracket and means for turning said clamping member into engagement with a wire article on said table, vertical adjustment of said bracket on said table being adapted to insure parallel relation between said table and said clamping member when the latter is in its wire clamping position.

13. In a wire knotting machine, a work supporting table movable in a horizontal plane and carrying blocks for positioning work thereon and a slide mounted on said table carrying a stop for engaging the free end of a wire article positioned by said blocks.

14. In a wire knotting machine, a work supporting table movable in a horizontal plane with respect to a rotatably driven knotting pinion, a slide mounted on said table carrying a wire stop and means for holding said slide stationary when said table is moved to carry a wire article thereon into position for operation upon by said pinion.
